UNITED STATES PATENT OFFICE

MICHAEL MARTE, OF EAST SYRACUSE, NEW YORK.

ROOFING-TILE.

No. 882,765.

Specification of Letters Patent. Patented March 24, 1908.

Application filed April 13, 1907. Serial No. 368,017.

To all whom it may concern:

Be it known that I, MICHAEL MARTE, a citizen of the United States, residing at East Syracuse, in the county of Onondaga, State 5 of New York, have invented certain new and useful Improvements in Roofing-Tiles; and I do hereby declare the following to be a full, clear, and exact description of the invention, such as will enable others skilled in the art to 10 which it appertains to make and use the same.

The present invention relates to improvements in roofing tiles, and it aims to provide an article of that nature, which may be constructed at an extremely low cost and which 15 is provided with a fastening device by means of which it is attached to the ordinary slating bars secured to the rafters, the fastening device being fixed in the tile in such a manner 20 as to be incapable of withdrawal therefrom.

Briefly described, the invention comprises a tile formed of baked clay and provided at its upper end with an attaching hook, whose stem portion is embedded therein during the 25 molding and prior to the firing of the clay.

The preferred embodiment of the invention is illustrated in the accompanying drawings in which like parts are designated by corresponding reference numerals in the several views.

Of the said drawings—Figure 1 is a front elevation of a portion of a tile covered roof. Fig. 2 is a longitudinal vertical section taken on the line 2—2 of Fig. 1. Fig. 3 is an enlarged detail view partly in section of one of the tiles.

Referring more particularly to the drawings, 5 designates generally, the rafters of the roof, 6 the horizontal slating-bars secured thereto, and 7 the tiles attached to the slating-bars.

Each tile, or imitation shingle, is formed of clay, molded and subsequently baked to provide the necessary durability and imper- 45 viousness to the weather. Prior, however, to

the final compression or molding of the clay, the stem portion 8 of a hook 9 is inserted into the mold at the upper end thereof, and is embedded in the clay; the molding is then completed, and the tile is subsequently fired. 50 Once baked, withdrawal of a hook is practically impossible, without a partial destruction of the tile in which it is fixed, since its stem portion is provided with a series of spurs; or similar projections 10 arranged in 55 staggered relation. It will be observed, therefore, from the foregoing, that a roof frame may be completely tiled in very much less time than is possible where ordinary 60 slates or shingles are used, since the tiles which form the subject of this case are attached to the slating-bars merely by catching the hooks therearound, as shown in Fig. 2, while the slates or shingles are individually nailed to the roof frame; that the above described tile is possessed of much greater durability than the wooden shingles for which it is a substitute, since it is completely impervious to the weather; and that the danger 65 of falling tiles is obviated by reason of the approximate impossibility of removal of the fastening hooks.

What is claimed, is—

—A roofing tile formed of baked clay and provided with a single attaching member 75 having its stem portion embedded in the upper end of the tile during the molding process and prior to the firing of the clay, said member having a laterally bent upper end adapted to form a hook for engagement 80 with the slating-bars of the roof, the embedded portion of said member being provided with spurs to prevent its withdrawal from the tile.

In testimony whereof, I affix my signature, 85 in presence of two witnesses.

MICHAEL MARTE.
